BUTTER CUTTER

William Grocoff, San Francisco, Calif.

Application January 26, 1946, Serial No. 643,515

4 Claims. (Cl. 31—25)

1

The present invention relates to improvements in butter cutters, and its principal object is to provide a convenient and effective machine for slicing a block of butter, preferably of the one-pound size, into a number of relatively thin squares, adapted for individual servings in restaurants, or the like.

At the present time this operation is usually performed by placing the block of butter on an open frame having a number of wires stretched thereacross, and by manually squeezing the butter through the frame. This is rather a laborious process, and very tiring on the operator.

In the present invention, it is proposed to provide a suitable machine in which a lever mechanism is used for forcing the butter through the frame, whereby the operation is much simplified, and can be carried out with much less effort on the part of the operator.

It is further proposed to provide certain improvements in the details of the machine, whereby the different parts are made to cooperate efficiently and without binding effect, and whereby the machine may be easily cleaned after use.

A still further object of my invention is to provide a novel cutter frame which facilitates the stretching of the wires across the same, and which is particularly well adapted for cooperation with the other parts of the machine.

Further objects and advantages of my invention will appear as the specification proceeds, and the novel features of the same will be fully defined in the claims forming part of this specification.

The preferred form of my invention is illustrated in the accompanying drawing, in which:

Figure 1 shows a top plan view of my machine;

Figure 2, a front view of the same;

Figure 3, a side view of my butter cutter with certain portions broken away to disclose interior construction;

Figure 4, a plan view of a cutter frame used in my machine; and

Figure 5, a section taken along 5—5 of Figure 4.

While I have shown only the preferred form of my invention, it should be understood that various changes or modifications may be made within the scope of the claims hereto attached without departing from the spirit of the invention.

Referring to the drawing in detail, my butter cutter comprises in its principal features, a base 1, a post 2 rising therefrom, a housing 3 supported by the post in spaced relation to the base, a guide frame 4 for supporting the cutter frame 5 in horizontal position above the base plate, a pres-

2

sure plate 6, and lever means 7 for operating the pressure plate.

The base 1 may be of any suitable construction, for giving substantial support to the remainder of the machine, and is here shown as comprising two legs 8 of channel iron arranged in V-shaped relation and joined, at the narrow end of the V, by a cross-member 9.

The underside of the base is preferably provided with a number of suction cups 10 for steady-
10 ing the base on its support, and to prevent mar-
ring of the surface on which the base may rest.

The cross-member 9 has the post 2 rising from its central portion, and the post supports the
15 housing 3 in spaced relation to the base.

The lower portion of the housing consists of a channel-guide 4 for the cutter frame 5. The guide consists of a channel bent into rectangular form, with the flanges presented inwardly to provide a rear member 11 and two side members 12, the front of the guide frame being open, except that the front ends of the members 12 are interconnected by a plate 13 lying in the plane of the lower channel flanges.

20 At the rear corners of the guide frame, the outer walls are removed for a short distance, as at 14, to render the channel accessible for clean-
ing purposes.

25 This guide frame is adapted to slidably receive the cutter frame 5 in the manner shown, and to support the latter in spaced relation to the base 1.

The inner edges of the guide frame have a superstructure rising therefrom comprising a rear wall 15 and side walls 16 arranged in rec-
30 tangular relation, and dimensioned for accom-
modating a block of butter therebetween. The side walls are sufficiently wide to bring the front edges thereof substantially flush with the front edge of the cutter frame.

35 The pressure plate 6 is dimensioned to sub-
stantially correspond to the upper surface of the block of butter to be cut, and to freely slide be-
tween the walls of the superstructure in horizon-
tal position.

40 The side walls 16 are formed with vertical slots
17, and the pressure plate has vertically elongated,
rectangular bearing members 18 projecting through the slots for guiding the pressure plate
when the same is moved vertically.

45 For moving the pressure plate, I provide the lever mechanism 7, including a lever 19 pivoted to the rear wall at the upper end thereof, as at 20, and connected to the pressure plate by means
50 of a pair of links 21 pivoted to the lever, as at

22, and to the pressure plate at spaced points, as at 23.

The lever 19 is of considerable length, and its free end extends forwardly beyond the base to give ample purchase for driving the pressure plate downwardly.

The cutter frame 5, illustrated in Figures 4 and 5, in detail, comprises a rectangular frame preferably made of angle iron, and presenting horizontal flanges 25 arranged in the same plane, 10 and vertical flanges 26 projecting downward from the inner edges thereof.

Two opposing horizontal flanges are formed with a large plurality of corresponding notches or slots 27 for anchoring a series of wires 28 spread across the upper face of the frame. Any suitable means may be used for anchoring the ends of these wires. The slots taper down to a point to allow the wires to become wedged therein.

The operation of my butter cutter will be readily understood from the foregoing description:

First the cutter frame is inserted in the channel-shaped guide frame 4 in the manner illustrated in Figures 2 and 3. The pressure plate is lifted by means of the lever 19, and a block of butter is placed on top of the cutter frame and underneath the pressure member. The latter is then forced downward by the lever 19, and the block of butter is forced downward through the cutter frame 5, and is thereby sliced into the desired number of squares, or sections.

The use of leverage means for forcing the pressure plate downward facilitates the operation so that the latter can be carried out without any considerable effort.

I claim:

1. In a butter cutter of the character described, a base, a post rising therefrom, a frame supported by the post and having horizontal guide ways and rear and side walls rising therefrom, a cutter frame receivable in the guide ways, a pressure plate movable between the walls above the cutter frame, a lever pivoted to the rear wall, and a link connection between the lever and the pressure plate for operating the latter, the guide ways being in the form of a rectangular channel having inwardly presented flanges and having openings at the corners in the outer wall thereof to give access for cleaning purposes.

2. In a butter cutter of the character described, a base, a post rising therefrom, a frame supported by the post and having horizontal guide ways and

5 rear and side walls rising therefrom, a cutter frame receivable in the guide ways, a pressure plate movable between the walls above the cutter frame, a lever pivoted to the rear wall, a link connection between the lever and the pressure plate for operating the latter, the guide ways being in the form of a rectangular channel having inwardly presented upper and lower flanges, and a plate connecting the forward ends of the lower flanges to serve as a guide for leading the cutter frame into the guide ways.

3. In a butter cutter of the character described, a base, a post rising therefrom, a frame supported by the post and having horizontal guide ways and rear and side walls rising therefrom, a cutter frame receivable in the guide ways, a pressure plate movable between the walls above the cutter frame, and means operable for forcing the pressure plate toward the cutter frame, the guide ways being in the form of a rectangular channel having inwardly presented flanges and having openings at the corners in the outer wall thereof to give access for cleaning purposes.

4. In a butter cutter of the character described, 25 a base, a post rising therefrom, a frame supported by the post and having horizontal guide ways and rear and side walls rising therefrom, a cutter frame receivable in the guide ways, means operable for forcing the pressure plate toward the cutter frame, the guide ways being in the form of a rectangular channel having inwardly presented upper and lower channels, and a plate connecting the forward ends of the lower flanges to serve as a guide for leading the cutter frame 30 into the guide ways.

WILLIAM GROCOFF.
